PHONOGRAPH RECORD RESURFACING
MACHINE

George H. Fritzinger, Orange, N. J., assignor
to Thomas A. Edison, Incorporated, West
Orange, N. J., a corporation of New Jersey

Application October 8, 1938, Serial No. 233,909

21 Claims. (Cl. 82—1.1)

This invention relates to phonograph record resurfacing machines, and more particularly to improvements in machines of the type employed for shaving or resurfacing wax-like or other records, such as are used in connection with commercial phonographs or dictating machines.

Records of the type described, which bear a recordation comprising a progressive groove cut or impressed on the surface of the record, may be prepared for re-use by a process of resurfacing. This process involves the cutting away of a layer, or layers, of the record material of an overall thickness that is at least equivalent to the maximum depth of the grooves forming the recordation. Machines for resurfacing such records commonly comprise a rotatable support for a record to be resurfaced; a carriage which is moved steadily across the record support, as from a start position into a terminal position, while the support is rotated; a resurfacing tool on the carriage which is movable into and out of an operative position with respect to the record; and a control device for starting and stopping the operation of the machine.

In taking a first or heavy cut on a record there is usually cut away a surface layer of sufficient thickness to completely obliterate the recordation. Such first or heavy cut may leave the record surface in a somewhat rough condition. In order that the record surface may, however, be rendered highly smooth, there is commonly provided a finishing-cut controlling means which, in its usual form, is arranged to advance the resurfacing tool a slight distance towards the record. During the operation of taking a first or heavy cut this finishing-cut controlling means is normally in an inoperative position; but whenever the record surface is found to be insufficiently smooth from such first cut, the finishing-cut controlling means may be moved into operative position and a second or finishing cut then taken.

It is an object of my invention to provide improved means for rendering record resurfacing machines of the above mentioned type more conveniently operable.

It is another object of my invention to provide novel and improved means which are arranged to facilitate the operation of taking a second or finishing cut.

It is a further object to effect such facility of operation by the provision of automatically-operated means controlled by the finishing-cut controlling means.

It is another object of my invention to provide improved means controlled and/or limited by the

finishing-cut controlling means, for starting and stopping the operation of the machine.

It is a further object to provide an improved and simplified control device which is adapted for both manual and automatic operation, the automatic operation being controlled and/or limited by the finishing-cut controlling means and being effected as an incident of completing a cut on the record.

It is another object to provide improved and novel means for automatically moving the resurfacing tool out of operative position.

It is a further object to provide improved means for automatically moving the tool out of operative position incidental to predetermined movements of the carriage.

Another object is to provide means controlled by the finishing-cut controlling means for moving the resurfacing tool out of operative position as an incident of returning the carriage to start position.

Other and allied objects will more fully appear from the following description and the appended claims.

In the description of my invention reference is had to the accompanying drawings, of which:

Figure 1 is a top plan view of a record resurfacing machine in which my invention is incorporated, the control device for starting and stopping the machine being shown in "on" position;

Fig. 2 is a vertical cross sectional view taken substantially along the line 2—2 of Fig. 1;

Fig. 3 is a fractional, vertical cross sectional view of the machine of Fig. 1, taken along the line 3—3 of Fig. 4 and otherwise generally similar to Fig. 2, but showing the carriage in an upwardly tilted position;

Fig. 4 is a top plan view of the control device for starting and stopping the machine, when this device is in "off" position; and

Fig. 5 is a fragmentary front view of the machine as of Fig. 1, partly in section and showing the inter-relationship between the carriage, the finishing-cut controlling means, and the control device for starting and stopping the operation of the machine, when the carriage is in its terminal position.

Reference being had to Figs. 1 and 2, there will be seen a phonograph record resurfacing machine in which my invention is incorporated and comprising a base plate 1 carrying a left-hand standard 2, right-hand standards 3 and 4, and an intermediate standard 5. In the right-hand portion of the base plate 1 there is also provided a

boss 6 on which there is pivotally mounted, as by a screw 7, an end-gate 8 normally held in closed position (as shown in Fig. 1) by a latch 9 pivoted to the right end portion 10 of a guide rail 11 which 5 extends laterally along the forward part of the machine. The end-gate 8 supports a conically pointed stud 12 adjustable with respect thereto as by an adjusting screw 13; the standard 2 supports another conically pointed stud 14 secured thereto by a set screw 15. The studs 14 and 12 form left and right thrust bearings for a shaft 16 which passes through an oversized hole 17 in the intermediate standard 5 and which carries a mandrel 18 for holding a cylindrical record 19 to be resurfaced. In the operation of mounting a record on, or removing a record from, the mandrel 18 the end-gate 8 is swung open to expose the right end of the mandrel. During the time the end-gate is open the shaft 16 is intermediate- 10 ly supported by the standard 5 and retained in engagement with the stud 14 by means of a collar 20, secured to the shaft by a screw 20', which abuts against the intermediate standard 5 to limit movement of the shaft in a rightward 15 direction.

When the end-gate 8 is closed the mandrel 18 is rotatably supported in parallel relation to the guide rail 11. Also in parallel relation to the guide rail is a laterally extending rod 21 supported by the left and right standards 2 and 3. Slidably and tiltably mounted on the rod 21 is a carriage 22 having a sleeve bearing 23 embracing the rod. As shown in Fig. 2, the carriage 22 has a relatively heavy arm 23 curved forwardly over the record 19 and terminating in a shoe 23' which normally slidably rests on the guide rail 11. In order that the carriage 22 may be moved steadily in a leftward direction across the mandrel 18 (as from its start position at the right 20 end of the mandrel into its terminal position indicated in dash-dot lines in Fig. 1) coincidentally with rotation of the record, there is provided a laterally extending feed screw 24 rotatably supported by the left and right standards 2 and 4 25 and having a pulley 25 adapted to be coupled, as by a belt (not shown), to a pulley 26 on the shaft 16. Secured to the carriage sleeve 23, as by the screws 27, is a resilient and rearwardly extending arm 28 carrying a feed-nut 29 which 30 normally engages the underside of the feed screw 24. As the carriage arm 23 is tilted upwardly into a position as shown in Fig. 3, the feed-nut 29 is moved downwardly free of the feed screw 24; the carriage may then be manually moved, 35 at will, across the record. To limit the upward tilting of the carriage arm 23 there is provided on the carriage an angularly extending arm 30 which is adapted to contact a stop or ridge 31 on the base plate 1.

On the right side of the carriage there is a 40 boss 32 which substantially overlies the rod 21. This boss carries a resurfacing tool 33 comprising a knife blade 34 mounted on a knife bar 35 which is slidably supported by the boss 32 for movement 45 towards and away from the record. The means for setting the resurfacing tool into operative position—a position of the tool in which the knife blade 34 engages the record—and for releasing the same may be of a well-known construction such as is disclosed in Luhr Patent No. 1,721,913, issued July 23, 1929, Machine for shaving sound record tablets, but is preferably of an improved construction such as is disclosed in Brown Patent No. 2,137,383, issued November 75 22, 1938, and entitled "Record shaving machine".

In the present instance, the tool-setting and releasing mechanism is sufficiently described by the following statements: A cap 36 is slidably mounted on the boss 32, guided by a guide rod 37, and suitably coupled to the knife bar 35 so 5 that when the cap is moved downwardly towards the record the knife bar 35 is yieldably moved therewith. The cap 36 is urged upwardly by a spring 38, but upward movement of the cap 36 relative to the bar 35 is limited by a head 39 10 of the bar. By reason of the upward biasing of the cap 36 the knife bar 35 is normally maintained in inoperative position, this position being defined by the contact of a collar 40 on the bar 35 with the underside 40' of the boss 32. The 15 setting and release of the tool 33 is controlled by a lever 41 pivoted on the right side of the boss 32 and having a short arm 42 which is coupled to the cap 36 by an angular link 43, the link being pivoted to the arm 42 by a pin 44 and to the cap 36 by a pivot screw 45; as the lever is 20 swung forwardly in a counter-clockwise direction the cap 36 and the knife bar 35 are moved towards the record and the knife bar is thereafter locked by a locking means such as is disclosed 25 in the abovementioned Brown patent, thereby effecting a setting of the tool into operative position. Such forward or setting movement of the lever 41 is limited to the position shown in Fig. 2 by the impingement of the link 43 against 30 the hub 41' of the lever. When the lever 41 is in this most forward position the pin 44 is slightly past dead center with respect to the pivot axes of the lever 41 and the pivot screw 45. The upward biasing force exerted on the cap 36 then causes the lever 41 to be urged in a counter-clockwise direction. It will therefore be apparent that when the lever 41 is moved in a counter-clockwise direction into its most forward position wherein its hub 41' contacts the link 43, the lever 35 is releasably held in that position and the tool 33 is yieldably maintained in operative position. It is also apparent that a slight "tripping" movement of the lever 41 in a clockwise direction such as to return the pin 44 across the dead 40 center line aforementioned will cause, by reason of the upward biasing of the cap 36, the tool 45 to be released from operative position.

In the operation of the machine the resurfacing tool is first set into operative position while the 50 carriage 22 is in an intermediate position overlying the record, the carriage is then moved into start position, and the record is then set into rotation as by a suitable motor (not shown) which may be located beneath the base plate 55 1 and be coupled to a pulley 46 on the shaft 16 as by a belt (not shown) which may pass through the opening 47 in the base plate. As the carriage 22 is fed across the record coincidentally with the rotation of the record, a surface layer of 60 the record is cut away, the cut-away layer being carried by a chip chute 48 downwardly through an opening 49 in the base plate. When the carriage has reached its terminal position, the tool 33 then having traversed the record, the operator 65 will normally do either of two things: Provided the record surface is sufficiently smooth from this first cut, he will remove the record from the machine; if, however, the record surface is insufficiently smooth from this first cut to receive 70 another recordation, he will take another cut on the record of a light or finishing character.

In order to facilitate the taking of a finishing cut there is provided a finishing-cut controlling means by which the tool 33 may be advanced a 75

slight distance towards the record without disturbing the initial setting of the tool. This finishing-cut controlling means comprises a short rod 50 mounted for pivotal movement about its longitudinal axis and extending through the shoe 23' of the carriage 22 in parallel relation to the guide rail 11. The rod 50 projects radially along its length below the shoe 23' throughout a minor portion of its periphery. Thus normally the carriage arm 23 is supported by the guide rail 11 by way of the rod 50. The rod 50 is, however, provided with a flat 51 throughout its length so that, as the rod is turned to bring the flat 51 into contact with the guide rail 11, the carriage arm 23 is lowered slightly to advance the tool 33 towards the record. On the rod 50 there is a forwardly extending bracket 52 by which the rod 50 may be manually turned. When the bracket 52 is in the position shown in Fig. 2, the flat 51 is off the guide rail 11 and the finishing-cut controlling means is therefore in inoperative position; when the bracket is, however, moved upwardly into a position such as is indicated in dash-dot lines in Fig. 3, the flat 51 is in position to contact the guide rail and the finishing-cut controlling means is therefore in operative position.

To facilitate the removal of a record from the machine there is provided a record ejector 53 comprising a handle 54 integral with a hub 54' and an upstanding arm 55, the hub being secured by a screw 54" to a pin 56 pivotally supported by the guide rail 11 and the intermediate standard 5. The arm 55 carries a shoe 57 bearing a cushion 58 adapted to contact the record in the operation of ejecting a record from the mandrel 18. The record ejector is normally maintained in an unoperated position, shown in Fig. 1, as by a coil spring 59. In the operation of the ejector the handle 54 is raised against the force of the spring 59 so as to move the cushion 58 rightwardly against the record to push the record off of the mandrel 18.

Coupled to the record ejector is a mandrel brake 60 which is operated incidental to the act of operating the record ejector. The mandrel brake 60 comprises an arm 61 bearing a shoe 62 and pivoted on the pin 56. The coupling between the record ejector 53 and the brake 60 comprises a spring 63 coiled about the hub 54' of the record ejector and hooked at one end about a forwardly extending pin 64 on the arm 61 and at the other end about a rearwardly extending pin 65 which is on the ejector to the right of the pin 64, the pins 64 and 65 thus being normally urged together. By these means it will be seen that the shoe 62 is yieldably moved into contact with the mandrel to retard by friction the rotation of the mandrel as the record ejector 53 is operated.

The above described structure and mechanism are common to record shaving machines heretofore manufactured and used, and form a part of the present invention only in so far as they are related to or combined with other mechanism hereinafter described.

The operation of a record resurfacing machine is greatly facilitated when the machine is automatically stopped at the completion of taking a cut on the record. The operator may then immediately inspect the record surface at the completion of such cut to ascertain whether or not another cut should be taken. It is, however, desirable that the operator be able to manually

start and stop the machine at will. It is a feature of my invention to provide a simple form of control device, comprising but a single switch, which is manually throwable into "on" and "off" positions to start and stop the machine, and which is moreover automatically thrown into "off" position at the completion of a cut on the record, as by the terminal movement of the carriage.

For reasons hereinafter explained, this control device is of a type which is biased into "on" position and which may be releasably locked in "off" position. Thus, the effecting of an "off" position of the control device is a matter of moving the control device into "off" position and then locking the same; whereas the effecting of "on" position is only a matter of releasing the lock on the control device.

This control device comprises a single-pole single-throw toggle switch 66 mounted on a bracket 67 secured by a screw 67' to the underside of the base plate 1. This switch may be suitably connected by way of a two-wire cable 68 in a motor or power supply circuit (not shown) for the machine so that the operation of the machine will be respectively stopped and started when the switch is thrown into "off" and "on" positions. The switch 66 has an operating lever 69 which extends forwardly and then upwardly through an opening 70 in the base plate 1. When the lever 69 is to the right, as shown in Fig. 1, the switch is in "on" position; when the lever 69 is to the left, as shown in Fig. 4, the switch is in "off" position.

The means for throwing the switch 66 between "on" and "off" positions comprises a laterally extending rod 71 slidably supported by the bosses 72 and 73 provided on the top side of the base plate 1 and respectively disposed to the left and right of the opening 70. As may be clearly seen in Fig. 5, the rod 71 is provided with a slot 74 engaged by the upper end portion 69' of the switch operating lever 69, the length of the slot 74 being slightly less than half the length of travel of the portion 69'. The rod 71 is restrained from turning by the engagement of a screw 85 in the boss 73 with a longitudinal slot 86 in the rod. The rod 71 is moreover biased rightwardly by a compression spring 75 carried within the boss 72 between the rod 71 and a plug 76 screwed into the boss, the rightward position of the rod 71 being defined by the impingement of a collar 77, secured to the rod by a screw 78, against the boss 73. When the rod 71 is in its rightward position, the switch 66 is in "on" position; when the rod 71 is moved leftwardly through a distance sufficient to move the lever 69 from its rightward position to a position slightly past dead center, the lever 69 will move onward throughout the length of the slot 74 into its leftward position, by reason of the toggle nature of the switch, to effect the "off" position of the switch. When the rod 71 is so moved it becomes locked by the engagement of a pawl 79 with a shoulder 80 formed by reducing the diameter of a portion of the rod 71. The pawl 79 is pivoted on an upright boss 81 by a pivot screw 82, and is biased into locking position by a spring 83 coiled about a reduced-diameter portion 81' of the boss 81 and hooked about the pawl and a pin 84 on the boss.

The means for manually throwing the switch 66 comprises a manually operable lever 87 pivoted on the guide rail 11 by a pivot screw 88. The lever 87 is coupled to the rod 71 by means of a relatively short arm or lever 89 also pivoted

about the pivot screw 88. The lever 89 is spaced slightly above the lever 87, as by a spacer 90 embracing the pivot screw 88, and is provided with a rounded forward end portion 89' which engages a slot 91 in the rod 71 as is shown in Fig. 4. Bent down from the lever 89 is a lug 92 which lies to the left of the lever 87. This lug 92 is connected by a light tension spring 93 to a downwardly bent lug 94 of a rightwardly extending arm 95 of the lever 87.

As the lever 87 is moved leftwardly it impinges against the lug 92 of the lever 89 to move the rod 71 leftwardly to throw the switch 66 into "off" position. When the lever 87 reaches its "off" position, as is shown in Fig. 4, the pawl 79 locks the rod 71 against rightward movement to retain the switch 66 in "off" position. In order that the initial rightward movement of the lever 87 from "off" to "on" position may unlock the switch 66, the lever 87 is provided with a pin 96 which, as the lever 87 is moved to the right, engages a cam face 97 on an arm 98 of the pawl 79 to move the pawl out of engagement with the shoulder 80 on the rod 71. It is for the reason that the lever 89 is locked against rightward movement during such initial rightward movement of the lever 87, that the lever 87 is yieldably connected, as by the spring 83, to the lever 89 to permit movement of the lever 87 in a rightward direction independently of the lever 89. When the rod 71 becomes unlocked the spring 75 moves the rod 71 rightwardly and thereby throws the switch 66 from "off" to "on" position.

In order that the switch may be thrown into "off" position at the completion of a cut on the record, the collar 77 on the rod 71 is provided with an upward extension 99, as may be seen in Figs. 2 and 3. On the shoe 23' of the carriage arm there is secured by the screw 100 a bracket 101 which extends downwardly in front of the guide rail 11. As the carriage moves into its terminal position, shown in Fig. 5, the bracket 101 contacts the extension 99 and thereby moves the rod 71 leftwardly to effect the "off" position of the switch 66.

If at the completion of a first or heavy cut on the record, the operator decides to take a finishing cut, the finishing-cut operation will be greatly facilitated by the provision of means for automatically restarting the machine as an incident of returning the carriage 22 to start position. To effect such automatic restarting of the machine, the pawl 79 is provided with an upstanding arm 102. On the bracket 52 of the finishing-cut controlling means there is provided a leftwardly and downwardly extending pin 103 which lies directly behind the arm 102 when the carriage is in its terminal position, as is shown in Fig. 5. Upon moving the bracket 52 upwardly to place the finishing-cut controlling means in an operative position, the pin 103 contacts the arm 102 to move the arm forwardly, thereby moving the pawl 79 to unlock the rod 71. It will, however, be seen that the switch 66 is not thrown into "on" position with the unlocking of the rod 71 since the rod is obstructed against rightward movement by the bracket 101 while the carriage 22 is in its terminal position. Upon the return of the carriage with the finishing-cut controlling means in operative position, the switch 66 will be so thrown by the spring 75, as by the release of the energy stored in this spring incidental to the movement of the carriage into its terminal position. With this arrangement it will be seen that should the operator move the carriage out

of its terminal position with the finishing-cut controlling means in inoperative position, such as is normally done when the tool 33 is to be reset for another heavy cut, the machine will not be automatically restarted since the switch 66 remains locked in "off" position. After the tool 33 is reset (which resetting can only be done while the record is out of rotation) the carriage is then placed into its start position and the machine is restarted by the manually operable lever 87.

5

10

In order that the pin 103 will not impinge upon the arm 102 at the completion of a finishing cut, as would occur upon moving the carriage through the end portion of its forward travel with the finishing-cut controlling means in operative position, there is provided a rearwardly extending pin 104 on the finishing-cut controlling means which engages, as the tool moves off of the left end of the record, a cam face 105 on a bar 106 secured, as by welding, to the inner-leftward side of the guide rail 11. By such engagement the finishing-cut controlling means is fully moved into its inoperative position as the carriage moves into its terminal position.

15

20

In the normal operation of the machine, the carriage is moved out of its terminal position with the finishing-cut controlling means in inoperative position only for the purpose of resetting the tool for the taking of a heavy cut on the record. In order to reset the tool it must

25

30

of course be first released from its set or operative position. In accordance with my invention this resetting of the tool is facilitated by the provision of means for automatically releasing the tool as an incident of moving the carriage out of its terminal position while the finishing-cut controlling means is in inoperative position. When the carriage is partially returned, the tool may be reset with respect to the record, the carriage then returned to start position and the machine restarted. It will, however, be seen that this automatic tool-releasing means is rendered inoperative when the finishing-cut controlling means is in operative position. Thus the return of the carriage with the finishing-cut controlling means in operative position, as in the act of performing a finishing-cut operation at the completion of a first or heavy cut on the record, will not effect the release of the tool. It may be noted that certain broad aspects of a means for automatically releasing the resurfacing tool, subject to the finishing-cut controlling means, are not claimed herein, but are claimed in a copending application of Richard M. Somers, Serial No. 272,565, filed May 9, 1939, and entitled "Phonograph record resurfacing machine", which application is connected by common ownership with the present application.

45

50

55

The means for automatically releasing the tool 33 from operative position comprises an angular arm 107 extending rearwardly and downwardly of the carriage and pivoted on the right side of the carriage by a pivot screw 108. Also pivoted on the screw 108 is a lever 109 which is spaced to the right of the arm 107 by a spacer 110 embracing the screw 108. The lever 109 is biased against a rightwardly extending pin 111 carried by the arm 107 by a tension spring 112 connected between a pin 113 carried by the lever 109 and a pin 114 carried by the arm 107, the lever 109 being suitably offset as along 115 so as to permit a reduction in the length of the pin 111. The forward arm 109' of the lever 109 normally contacts the underside of the short arm 42 of the tool-setting lever 41, such contact being main-

60

65

70

75

tained by means of a light tension spring 116 which urges the arm 109' upwardly, the spring 116 being connected between a pin 117 on the carriage and the aforementioned pin 111 carried by the arm 107. Although the arm 109' is normally urged upwardly against the arm 42, it is not urged sufficiently to effect a release of the tool 33 from operative position. Upward movement of the arm 109' is limited, as when the resurfacing tool is out of operative position, by the contact of the arm 109' with a rightwardly extending pin 32' on the boss 32.

At the lower end of the arm 107 there is provided a turned over lug in the form of a downwardly extending blade 118. On the top side of the base plate 1 there is secured, by the screw 119 and guiding pins 120, a short bar 121 having a cam face 122. When the carriage arm 23 is resting on the guide rail 11, the blade 118 clears the bar 121, as is shown in Fig. 2. When, however, the carriage arm 23 is in an upwardly tilted position to free the feed nut 29 from the feed screw 24, the blade 118 is in such position as to engage the cam face 122 during the movement of the carriage out of its terminal position, as is shown in Fig. 3. By such engagement the arm 107 is moved forwardly and the arm 109' of the lever 109 is moved sufficiently upwardly to effect the release of the resurfacing tool 33 from operative position.

In order that the resurfacing tool will not be released by the return of the carriage when the finishing-cut controlling means is in operative position, there is provided on the right side of the carriage arm 23 a bar 123 slidably mounted by front and back shoulder screws 124 and 125 which pass through the respective front and back elongated slots 126 and 127 of the bar 123 and thread into the respective bosses 126' and 127' on the carriage arm. The bar 123 is coupled to the finishing-cut controlling means by a downwardly extending arm 128, at the forward end of the bar, having a turned-over lug 129 in which there is provided an opening 130. Passing through the opening 130 is a pin 131 secured to the rod 50 of the finishing-cut controlling means. The coupling between the finishing-cut controlling means and the bar 123 is arranged so that the bar 123 is in its most forward position when the finishing-cut controlling means is in inoperative position, the bar 123 being moved into its rearward position and returned to forward position as the finishing-cut controlling means is moved into operative position and returned to inoperative position.

The rearward end 123' of the bar 123 is provided with an angular cam face 132 on its underside. As the bar 123 is moved into its rearward position, as by the movement of the finishing-cut controlling means into operative position, the cam face 132 engages a lateral pin 133 carried by a forward extension 134 of the aforementioned arm 109' of the automatic tool-releasing means. By such engagement of the cam face 132 with the pin 133, the arm 109' is moved slightly downwardly free of the arm 42 of the tool-setting lever 41, the pin 133 coming to rest in a detent 132' on the bar when the bar reaches its rearward position so as to releasably hold the finishing-cut controlling means in operative position. Thus when the finishing-cut controlling means is in operative position the arm 109' is blocked against movement to release the tool from operative position. When the finishing-cut controlling means is, however, in inoperative position the

arm 109' is fully free of the bar 123 and may therefore be moved upwardly, as by the return of the carriage, to effect the release of the tool 33 from operative position.

It will be seen that unless the arm 109' is moved downwardly through a considerable distance by the movement of the finishing-cut controlling means into operative position, the blade 118 will yet engage the cam face 122 of the bar 121, and the arm 107 will be thereby moved forwardly, as an incident of returning the carriage. To permit such movement of the arm 107 while the arm 109' is blocked against upward movement, the arm 107 is resiliently connected to the lever 109 by the spring 112, as hereinbefore described.

Although I have herein described and illustrated a preferred embodiment of my invention it will be understood that this embodiment is subject to many changes and modifications without departure from the scope of my invention, which I undertake to express according to the following claims.

I claim:

1. In a phonograph record resurfacing machine adapted for taking cuts from a record: in combination, a carriage; a finishing-cut controlling means having operative and inoperative positions; a control device for starting and stopping the operation of the machine; means for causing an automatic operation of said control device incidental to predetermined movements of said carriage; and means, operatively connected with said finishing-cut controlling means, for limiting the automatic operation of said control device.

2. In a phonograph record resurfacing machine having a resurfacing tool for taking cuts from a record: in combination, a carriage movable into and out of a terminal position; a finishing-cut controlling means associated with said tool and having operative and inoperative positions; a control device for starting and stopping the operation of the machine; means for causing an automatic operation of said control device to stop and start the operation of the machine incidental to movements of said carriage into and out of its terminal position; and means, operatively connected with said finishing-cut controlling means, for controlling the automatic operation of said control device.

3. In a phonograph record resurfacing machine having a support for a record and means for taking cuts from the record: in combination, a carriage capable of forward and return movement across said support; a finishing-cut controlling means movable into an operative position; a control device movable to start and stop the machine; and means, operated incidental to the return of the carriage when said finishing-cut controlling means is in operative position, for moving said control device to start the machine.

4. In a phonograph record resurfacing machine having a resurfacing tool for taking cuts from a record: in combination, a carriage movable into terminal and start positions; a finishing-cut controlling means associated with said tool and movable into an operative position; a control device automatically operated to stop the operation of the machine as said carriage is moved into terminal position; and means for operating said control device to start the machine as said carriage is returned to start position while said finishing-cut controlling means is in operative position.

5. In a phonograph record resurfacing machine adapted for taking cuts from a record: in combination, a movably mounted carriage; a finishing-cut controlling means having operative and inoperative positions; a device for controlling the operation of the machine having "off" and "on" positions, said device being biased into one of its said positions and being operated into the other of its said positions as said carriage is moved into said terminal position; releasable means for holding said device in said other position; and means, controlled by said finishing-cut controlling means, for releasing said holding means. 5

16. In a phonograph record resurfacing machine adapted for taking cuts from a record: in combination, a movably mounted carriage; a finishing-cut controlling means having operative and inoperative positions; a control device for said machine having "on" and "off" positions; means biasing said control device into "on" position; releasable means for holding said control device in "off" position; and means, operated as said finishing-cut controlling means is moved into operative position, for releasing said holding means. 10 15 20 25 30 35 40 45 50 55 60 65 70 75
17. In a phonograph record resurfacing machine having a support for a record and means for taking cuts from the record: in combination, a carriage capable of forward and return movements across said support; a finishing-cut controlling means having operative and inoperative positions; a control device for said machine having "on" and "off" positions; operating means adapted to move said control device from "off" to "on" position incidental to the return of said carriage while said finishing-cut controlling means is in operative position; and means associated with said operating means to cause said control device to be retained in "off" position incidental to the return of said carriage while said finishing-cut controlling means is in inoperative position. 30 35 40 45 50 55 60 65 70 75
18. In a phonograph record resurfacing machine having a support for a record: in combination, a carriage capable of forward and return movements across said support; a control device comprising a single switch for starting and stopping the operation of the machine; means for causing said control device to be automatically operated as an incident of moving said carriage through a predetermined portion of its travel; and means, operable when said carriage is out of said predetermined portion, for manually operating said control device. 45 50 55 60 65 70 75
19. In a phonograph record resurfacing machine: in combination, a movably mounted carriage; a switch for controlling said machine having "on" and "off" positions; means biasing said switch into one of its said positions; locking means for retaining said switch in the other of its said positions; means for operating said switch as an incident of moving said carriage; and means manually operable in one direction to release said locking means and in the other direction to operate said switch into the other of its said positions. 55 60 65 70 75
20. In a phonograph record resurfacing machine adapted for taking cuts from a record: in combination, a carriage movable between start and terminal positions; a finishing-cut controlling means having operative and inoperative positions; a control device having "on" and "off" positions for starting and stopping the operation of the machine; means for releasably holding said control device in "off" position; means, operable when said carriage is in its terminal position, for releasing said holding means as said finishing-cut controlling means is moved into operative position; and means for automatically returning said finishing-cut controlling means to inoperative position as an incident of moving said carriage into its terminal position at the completion of a finishing cut on the record. 5
- 25 30 35 40 45 50 55 60 65 70 75
21. In a phonograph record resurfacing machine having a support for a record: in combination, a carriage movable across said support between terminal and start positions; a resurfacing tool on said carriage movable into an operative position with respect to a supported record; and means, operated incidental to the return of said carriage to start position, for moving said resurfacing tool out of operative position. 10 15 20 25 30 35 40 45 50 55 60 65 70 75
22. In a phonograph record resurfacing machine having a frame and a support for a record: in combination, a cam member on said frame; a carriage movable relative to said support; a resurfacing tool on said carriage movable into an operative position with respect to the record; and means, carried by said carriage and operated by said cam member as an incident of moving said carriage through a predetermined portion of its travel, for moving said resurfacing tool out of operative position. 20 25 30 35 40 45 50 55 60 65 70 75
23. In a phonograph record resurfacing machine having a support for a record: in combination, a carriage capable of forward and return movements across said support; a resurfacing tool on said carriage movable into operative position with respect to a supported record; a finishing-cut controlling means for advancing the tool towards the record; and means, controlled by said finishing-cut controlling means, for causing an automatic movement of said resurfacing tool out of operative position incidental to a return movement of said carriage. 30 35 40 45 50 55 60 65 70 75
24. In a phonograph record resurfacing machine having a support for a record: in combination, a carriage capable of forward and return movements across said support; a resurfacing tool on said carriage movable into an operative position relative to the record; a finishing-cut controlling means associated with said tool having an inoperative position; and means, operated incidental to the return of said carriage when said finishing-cut controlling means is in inoperative position, for moving said tool out of operative position. 45 50 55 60 65 70 75
25. In a phonograph record resurfacing machine having a support for a record: in combination, a carriage movable across said support; a resurfacing tool on said carriage movable into an operative position with respect to the record; a finishing-cut controlling means having operative and inoperative positions; yieldable means, actuated incidental to predetermined movements of said carriage, for moving said tool out of operative position; and means, controlled in accordance with the position of said finishing-cut controlling means, for obstructing the operation of said tool-moving means. 55 60 65 70 75
26. In a phonograph record resurfacing machine having a support for a record: in combination, a tiltably and otherwise movably mounted carriage; a resurfacing tool on said carriage movable into operative position with respect to the record; and means, operated by movement of the carriage while said carriage is in a tilted position, for moving said resurfacing tool out of operative position. 70 75

17. In a phonograph record resurfacing machine having a frame and a support for a record: in combination, a carriage movable relative to said support; a resurfacing tool on said carriage movable into an operative position; a finishing-cut controlling means movable into operative position to advance said tool towards the record; a cam member on said frame; means, operated by said cam member as said carriage is moved, for moving said tool out of operative position; and means, carried by said carriage, for rendering said tool-moving means inoperative when said finishing-cut controlling means is in operative position.
18. In a phonograph record resurfacing machine having a support for a record: in combination, a carriage; a resurfacing tool movable into operative position with relation to the record; a finishing-cut controlling means having operative and inoperative positions; means, mounted on said carriage and operated by movement of the carriage, for causing said tool to be moved out of operative position; and means for rendering said tool-moving means inoperative when said finishing-cut controlling means is in operative position.
19. In a phonograph record resurfacing machine having a support for a record: in combination; a carriage, a resurfacing tool on said carriage movable into operative position with respect to the record; a finishing-cut controlling means

for advancing said tool towards the record; a control device for starting and stopping the operation of the machine; means for moving said tool out of operative position; and means, controlled by said finishing-cut controlling means, for operating both said control means and said tool-moving means.

20. In a phonograph record resurfacing machine adapted for taking cuts from a record: in combination, a carriage movable between terminal and start positions; control means movable into "on" and "off" positions to start and stop the operation of the machine; means, operated as said carriage is moved into its terminal position, for storing energy and for moving said control means into "off" position; and means for releasing said energy to move said control means into "on" position.

21. In a phonograph record resurfacing machine adapted for taking cuts from a record: in combination, a movably mounted carriage; a stationary cam member; a resurfacing tool on said carriage settable into operative position relative to the record; and means, mounted on said carriage and controlled by said cam member, for causing said tool to be moved out of operative position incidental to a predetermined movement of the carriage.

GEORGE H. FRITZINGER.

CERTIFICATE OF CORRECTION.

Patent No. 2,192,597.

March 5, 1940.

GEORGE H. FRITZINGER.

It is hereby certified that error appears in the printed specification of the above numbered patent requiring correction as follows: Page 2, first column, line 71, after "1929," insert --and entitled--; same page, second column, line 42, strike out the word "yieldably"; and that the said Letters Patent should be read with this correction therein that the same may conform to the record of the case in the Patent Office.

Signed and sealed this 30th day of July, A. D. 1940.

(Seal)

Henry Van Arsdale,
Acting Commissioner of Patents.
